UNITED STATES PATENT OFFICE.

MORRIS HAZEN, OF CINCINNATI, OHIO.

AUTOMOBILE RADIATOR CORE AND METHOD OF MANUFACTURING THE SAME.

Application filed April 28, 1924. Serial No. 709,429.

My invention relates to radiator cores particularly adapted for use in connection with internal combustion engines.

Heretofore it has been the practice, in manufacturing automobile radiator cores, to form sheet material which when cut and seamed together comprises a plurality of tubes adapted when combined with other sections to admit the flow of water thereover and then in forming a fin from a separate sheet of material by a different operation and adapted to be inserted between the first said sheet thereby separating the tubes and providing spaces therebetween for the purpose of permitting circulation of the air through said tubes whereby the temperature of said water is adapted to be lowered.

The objects of my invention are to provide means whereby the construction of radiator cores is greatly simplified; to provide means whereby a core is adapted to be manufactured from a plurality of flat pieces of sheet metal, each piece of which is formed by a usual stamping process and comprises a part of said core; to provide a radiator core adapted to be constructed from a plurality of pieces of sheet metal formed similar to one another, thereby greatly reducing the cost of manufacturing said core.

My invention consists in forming a plurality of pieces of sheet metal so that when one end of each piece is bent upon one portion of itself and the remaining end is bent upon another portion of itself, a section is formed comprising a plurality of tubes in stepped relation to one another and having air passages therethrough and therebetween; and in providing each section adapted to be connected to adjacent sections to permit the flow of water over said tubes for the purpose of cooling said water.

My invention further consists in the details of construction, combination, arrangement and location of parts, as herein set forth and claimed.

In the drawing:

Fig. 1 is an end elevation showing two sections of my radiator in partly completed assembled position;

Fig. 2 is a perspective view of a plurality of sections of my invention in assembled position and ready for installation showing the sections broken away;

Fig. 3 is a midway vertical cross section of the view shown in Fig. 1;

Fig. 4 is a front elevation of one-half of a single piece of sheet material cut longitudinally after being formed and showing the same broken away and before being bent into proper position for assembling;

60

Fig. 5 is a cross section taken on a line corresponding to 5—5 of Fig. 4; and

Fig. 6 is a cross section taken on the line corresponding to 6—6 of Fig. 4 after the sheet material is bent upon itself and ready 65 for being assembled with other similar sections for forming the completed core of a radiator.

In the preferred construction of my invention, I provide sheet 1 having a plurality of 70 stamped ribs or ridges 2 extending transversely of the sheet. Each rib 2 consists of an intermediate semi-cylindrical portion 3 integral with angular end portions 4 and respectively in substantially parallel alignment therewith. Angular portions 4, respectively, are adjacent longitudinal edges 5 of sheet 1 and respectively consist of angular sides 6 and 6' respectively having their outer edges connected by integral plates 7 and 8, 80 respectively positioned outwardly from semi-cylindrical portions 3 whereby an air space is formed between the respective semi-cylindrical portions when sheet 1 is bent upon itself with plates 7 in engagement with 85 each other or when plates 7 are in engagement with plates 8, as the case may be.

Plates 8 are positioned a greater distance outwardly from semi-cylindrical portions 3 than are plates 7, thereby providing step 9 90 having greater depth than step 10 whereby the respective air and water spaces are formed as will be hereinafter explained.

Ribs 2 are arranged in groups 11, 12 and 13. Groups 12 and 13 are spaced apart by 95 integral flat plate 14 extending the full width of sheet 1 and in parallel relation to plates 7 and 8.

Groups 11 and 12 are connected by angular plate 15 integrally connected to one-half 100 portions 16 and 17, respectively, of ribs 2.

Sheet 1 is formed, as shown in Figs. 4 and 5, by a usual stamping press and when completely formed and bent twice upon itself comprises section 18 adapted to fit adjacent 105 other similar sections for providing the water spaces of a radiator core, as will herein-after be explained. A single piece of flat sheet material is preferably inserted into the press and formed in one operation, thereby 110

greatly reducing the cost of manufacturing a completed core.

The length of sheet 1 is entirely dependent upon the required capacity and size of the 5 radiator core desired and the width of the sheet represents the thickness of the completed core.

Sheet 1, after being formed, is bent upon itself, as shown in Fig. 6, with the outwardly 10 extending end 19 into engagement with half-rib 17 thereby providing layers 20 and 21 of section 18 having plates 7 of layer 20 in engagement and registering with plates 7 of layer 21, whereby air spaces 22, as shown in 15 Fig. 3, are formed between semi-cylindrical portions 3, having a width equal to twice the depth of step 10. Plate 14 has its central portion bent upon itself forming extension 23 which permits edges 24 and 25 of the 20 plate, respectively, to remain in alinement with plates 8, respectively, of layers 20 and 21. End 26 of sheet 1 is then bent upon layer 21 so that flange 27 fits over and in 25 close engagement with edge 24 of plate 14, and plates 7 are brought into registering engagement with plates 8 whereby air spaces 28 are formed. Air spaces 28 have a width, 30 between semi-cylindrical portions 3, equal to the combined depth of steps 9 and 10 for permitting air to circulate from air spaces 29 into air spaces 22', respectively, within semi-cylindrical portions 3. Angular member 15 comprises end 15' of layers 20 and 31 and integral half ribs 16 and 17, respectively, are 35 arranged in alined relation with plates 8 and 7, respectively, of layers 31 and 20.

Tubes 29 are formed by layers 20 and 21 and tubes 30 are formed by layers 21 and 31. The tubes are at each end of the respective 40 cylindrical portions 3 for forming tubes for engaging angular portions 4, and a water space is formed between the respective semi-cylindrical portions 3 when the contacting angular portions 4 are "nested" 45 into each other.

Extension 23 of plate 14 is bent and soldered into engagement with flange 27 whereby section 18 is completed and ready for being assembled with other similar sections.

Core 18', as shown in Fig. 2, is formed by placing one section 18 in engagement with other similar sections so that ends 15' and plates 14, respectively, are in alinement with one another, whereby angular end portions 4 of one section fit into angular end portions 4 of the adjacent sections and angular sides 6 and 6', respectively, of the engaging angular end portions are parallel with each other. Plates 8 of layer 20, respectively, are in engagement with plates 7 of layer 31 of the adjacent section, thereby providing water space 32 between the adjoining sections, as shown in Fig. 3. The outer ends of tubes 29 and 30 of core 18' are secured together by suitable 60 means, as by inserting the edges of the tubes 65

in a bath of solder or other suitable adhesive material, whereby the contacting angular portions 4 are sealed and the completed core is securely fastened together.

Water space 32 has a width equal to the 70 depth of step 9 less the depth of offset 10, which may vary dependent upon the size of the core and the water capacity of the internal combustion engine to which the core is applied. 75

Slots 33, as shown in Fig. 2, at top 34 of core 18', are for the purpose of permitting the entrance of water from the usual radiator water reservoir, so that the water may drain downwardly through water spaces 32 80 and over the exterior surface of tubes 29 and 30 thereby cooling the same, whereby the temperature of the water within the radiator core, is adapted to be lowered for the reason that the heat of the water is radiated to the 85 tubes and the passage of air through the tubes prevents the temperature of the same from reaching an abnormally high point.

As heretofore explained plates 7 and 8 prevent semi-cylindrical tubes 3 from contacting each other, thereby providing air spaces between the tubes for the purpose of permitting the free flow of air between the tubes as well as through them in order that the heat transmitted by the water to the metal in the 95 tubes may be thoroughly radiated and carried from within the core by the currents of air passing therethrough.

While I have shown the outer portions of tubes 29 and 30 representing a regular polygon and the central portions of the tube circular in form, it is merely my preferred construction and I desire to emphasize the fact that the shape of the tubes may be varied to any desired shape for the purpose of accomplishing the desired result. 100

By forming sheet 1 in one operation, then bending the sheet twice upon itself, then forming extension 23 and bending the same in engagement with flange 27 of the sheet, 110 the complete work of forming section 18 is finished in comparatively a few operations requiring a short period of time, thereby effecting great economy in the construction of a radiator core having great efficiency. 115

I may form sections 18 by the method of bending sheet 1 upon itself only once, thereby providing each section with but two thicknesses of material whereby water when admitted into slots 33 is adapted to flow over the complete outer surface of the tubes, or sheet 1 may be so formed that it may be bent upon itself many more times than shown in Fig. 6. 120

An advantage of my invention is that in the course of manufacturing my radiator core, I merely provide myself with a plurality of flat pieces of sheet material which are successively inserted into a suitable press and one operation of said press is sufficient 125 130

to form a piece completely and ready for the bending operations, after which a section is ready for being assembled with other sections to form a radiator core of the required 5 capacity.

Another advantage is by the use of my invention the cost of manufacturing a radiator core is greatly reduced to such an extent that if an automobile user, having a radiator 10 of my manufacture, is unfortunate in considerably damaging said core, as by a collision, the same may be removed and a new one completely substituted therefor at a low cost. In fact, my radiator core may 15 be manufactured and sold at such a low price that it will cost considerably more to repair the core, after being damaged by a heavy impact, than it would be to discard the damaged core and substitute therefor a 20 new one of my construction.

It is well known that the high cost of labor enters materially into the manufacturing cost of radiator cores. But by my 25 method of constructing a core I eliminate a considerable part of the usual cost of labor, for the reason that a single piece of flat sheet material is formed, by a suitable press, completely and ready for being further formed, 30 assembled and installed with other similarly formed sections, whereby a completed radiator core is quickly and efficiently built to the proper size, depending upon the water cooling capacity required.

It is apparent that I have invented a simple, efficient and practical radiator core and that each section of the core is formed from 35 a single piece of flat sheet material similar to one another after which the same is bent to a shape as heretofore explained, whereby 40 it is not necessary to manufacture a plurality of dissimilar parts which necessitates the use of various shaped dies and various complicated operations in the usual course of manufacture.

While I have chosen to illustrate the form 45 and structure of my invention by the herein drawings and explanations of the same, I desire to state that the form and the explanations, as relates thereof, are not intended to include the various forms or modification in which my invention may be incorporated. The herein illustrations and 50 explanation are made merely for the purpose of showing one form of construction by which my invention may be carried into effect.

While I have shown and described a particular construction, such for instance, as a 55 single flat piece of sheet material being formed and then twice bent upon itself thereby providing three thicknesses of material in a complete section, it is apparent that the number of bends and the number of thicknesses of material attained, is merely a matter of selection.

My invention resides in the combination and arrangement of parts and the details of construction, as hereinafter claimed, it being understood that changes in the precise embodiment of the invention herein disclosed 70 can be made within the scope of what is claimed without departing from the spirit of the invention.

What I claim as new and desire to secure 75 by Letters Patent is:

1. A radiator core comprising a plurality of sections, each section comprising a plurality of pairs of aligned end tubes and a corrugated portion intermediate said pairs of end tubes, each corrugated portion being 80 offset with respect to the end portions, thereby providing air communicating means between the vertically aligned tubes, the walls of one section being adapted to fit in the walls of the adjacent section in spaced apart 85 relation intermediate the ends whereby a water space is formed between said sections.

2. A radiator core comprising a plurality of sections, each section comprising a plurality of corrugated end portions having their intermediate portions offset laterally therefrom and said end portions connected together whereby a plurality of vertically aligned tubes are formed for the purpose of providing air spaces between the respective 90 adjacent vertically aligned tubes, the wall of each section being adapted to fit into the wall of an adjacent section whereby a water space is formed between said sections and each of said sections having its end portions 95 adapted to maintain the several layers of said section in close engagement with each other.

3. A method of manufacturing a radiator core comprising first forming a sheet of 100 metal with a plurality of spaced apart ribs arranged in groups and having a flat plate intermediately connecting two of said groups and having an angular plate integrally connecting two of said groups, each 105 of said ribs comprising angular end portions having flat tops and a partial-cylindrical portion integrally connected intermediate said angular end portions and stepped therefrom, then bending one end of said sheet in engagement with itself approximately at a point one-third distance from the opposite end of said sheet whereby said flat portions of said angular portions are 110 respectively adapted to engage each other whereby a plurality of aligned polygonal tubes are formed having integrally connected intermediate end stepped partial tubes 115 whereby an air space is formed between said partial-cylindrical portions, then bending the remaining end of said sheet around said first end and in engagement with said flat plate, then in securing the outer sides of said polygonal tubes in engagement and fitted into the outer sides of similar tubes 120 125 130

of another formed plate, whereby a water space is formed between said formed plates.

4. A radiator core comprising a plurality of sections, each section consisting of a formed plate having transverse spaced corrugations therein, angular portions at each end of said corrugations, a semi-cylindrical portion intermediate said angular portions and having its outer surface out of the plane of said angular portions, said plate adapted to be bent twice upon itself whereby said angular portions are respectively adapted to engage and register with respective angular portions whereby air spaces are formed between said semi-cylindrical portions and said angular portions of said section adapted to fit in the respective angular portions of an adjacent section whereby a water space is formed between the adjacent semi-cylindrical portion of said sections.

5. A radiator core comprising a plurality of sections each section consisting of a formed plate having transverse spaced corrugations therein, angular portions at each end of said corrugations, a semi-cylindrical portion intermediate said angular portions and having its outer surface out of the plane of said angular portions, said plate adapted to be bent upon itself whereby said angular portions are respectively adapted to engage and register with said respective angular portions whereby air spaces are formed between said semi-cylindrical portions and said angular portions of said section adapted to fit in the respective angular portions of an adjacent section whereby a water space is formed between the adjacent semi-cylindrical portions of said sections.

6. A radiator core comprising a plurality of sections, each section consisting of a formed plate having transverse spaced corrugations, said plate being provided with

end portions and an intermediate portion having its surfaces out of the plane of said end portions, said plate adapted to be bent twice upon itself whereby the respective end portions of the formed section are adapted to engage and register with each other whereby continuous air spaces are formed between said intermediate portions, and said end portions of said completed section adapted to engage and fit similar end portions of an adjacent section whereby a continuous water space is formed between the adjacent intermediate portions of said sections, respectively.

7. The method of manufacturing a sectional radiator core comprising first forming a single sheet of metal with a plurality of spaced apart transverse corrugations having their ridges extending in opposite directions, said corrugations being arranged in groups having an integral part connecting two of said groups and having another integral part connecting two of said groups, each of said groups having its ridges intermediate its ends out of the plane of its end portions, then bending one end group upon the middle group and bending the other end group upon said first mentioned end group whereby a plurality of horizontally disposed air tubes with air passages connecting the respective air tubes, are formed for the passage of continuous sheets of air, thereby permitting the air to freely circulate from top to bottom, both horizontally and vertically through each section, then assembling said section in engagement with other similar sections and fitting them into the outer sides of similar tubes, whereby a continuous water space is formed between the respective sections, and then suitably securing the free ends of said groups of the several sections.

MORRIS HAZEN.
